UNITED STATES PATENT OFFICE.

GEORGE O. EBERHARDT, OF KELLIHER, MINNESOTA, ASSIGNOR OF ONE-HALF TO
JOSEPH JEROME, OF BATTLE RIVER, MINNESOTA.

OIL STRAINER AND SEDIMENT TRAP.

1,378,334.

Specification of Letters Patent. Patented May 17, 1921.

Application filed October 16, 1919. Serial No. 331,030.

To all whom it may concern:

Be it known that I, GEORGE O. EBERHARDT, a citizen of the United States, residing at Kelliher, in the county of Beltrami and 5 State of Minnesota, have invented certain new and useful Improvements in an Oil Strainer and Sediment Trap, of which the following is a specification.

My invention relates to new and useful 10 improvements in an oil strainer and sediment trap and more particularly to a device of this character adapted to be attached to the oil pipe of a Ford automobile.

The principal object of the invention is 15 the provision of an oil strainer and sediment trap so constructed as to fit around the funnel end of the Ford oil pipe so that it will strain the oil which is picked up by the fly wheel and magnet before being dropped 20 into the funnel of the oil pipes.

Another object of the invention resides in the provision of a trap adapted to receive and hold the sediment which is strained from the oil.

25 A further object of the invention consists in the provision of novel means for connecting the strainer and sediment trap to the oil pipe and to the cylinder block.

With these and other objects in view my 30 invention consists in the novel details of construction and arrangement of parts which will be more clearly understood from the following specification and drawings in which:—

35 Figure 1 is a front elevation.

Fig. 2 is a rear elevation.

Fig. 3 is a section on the line 3—3 of Fig. 1 looking in the direction of the arrow and

40 Fig. 4 is a transverse vertical section on the line 4—4 of Fig. 1 looking in the direction of the arrow.

In the drawings the numeral 1 indicates the oil pipe having an enlargement on the 45 top thereof forming a funnel 2. This funnel 2 is preferably elongated in shape as more clearly illustrated in Fig. 1 of the drawing and a flexible tongue 3 is formed on the rear of the enlargement or funnel 2 for a purpose to be later described. This 50 tongue is provided with an opening 4 as illustrated more particularly in Figs. 2 and 3 of the drawing.

My strainer and sediment trap comprises 55 a housing adapted to be secured around the

oil pipe and funnel and a cover adapted to be secured to the housing over the top of the funnel. This housing comprises a back 5, front 6, sides 7, and bottom 8. As illustrated more particularly in Fig. 4 of the drawings the back 5 is of greater height than the front 6 and the sides 7 are inclined to connect the front and back. The upper edge of the back is bent to form a flange 9 illustrated at 9 for a purpose to be later 65 described. The front 6 is cut away as indicated at 10, below the upper edge, for a purpose to be later described. The front 6 is provided with a plurality of vertically 70 extending slots 11 which terminate below the lower edge of the cutout portion 10 as more particularly illustrated in Fig. 1 of the drawings. The lower edge of the cutout portion is curved outwardly as indicated at 12 and this curved portion extends beyond 75 the sides and front of the housing. The front plate 6 is provided with the right angled extension 13, more clearly illustrated in Fig. 3 of the drawings, and this right angled extension is adapted to overlie one 80 side 7 and is secured thereto by means of a rivet or other suitable fastening means 14. The front plate 6 is preferably formed integral with one side 7 and the lower edge of this front plate is also provided with the 85 inturned flange 15 adapted to extend beneath the bottom 8 of the housing.

The housing is provided in its back 5 with an elongated opening 16 which extends at an angle as more clearly illustrated in Fig. 90 2 of the drawings. The tongue 3 of the funnel 2 is adapted to extend through this elongated opening and be bent parallel with the back as more clearly illustrated in Figs. 2 and 3 of the drawings. The back is also 95 provided with an opening adapted to register with the opening 4 in the tongue 3 when the same is bent parallel with the back 5.

The lower end of the oil pipe 1 is adapted 100 to pass through an opening in the back 5 adjacent the lower end and this opening is indicated at 17 in Fig. 4 of the drawings.

The cover is adapted to be secured over the open top of the housing and this cover 105 comprises a plate 18 having a plurality of longitudinally spaced flexible tongues 19 formed on the lower edge thereof. The plate 18 is adapted to engage the flange 9 formed on the upper edge of the back 5, 110

as more particularly illustrated in Figs. 3 and 4 of the drawings, and the ends of the tongues 19 are adapted to be bent downwardly as indicated at 20 to engage over the top edge of the front plate 6. The spaces between the tongues 19 form openings for a purpose to be later described.

As stated in the objects of my invention I provide a strainer and sediment trap 10 which is particularly adapted for use with the oil pipe of a Ford automobile. The oil pipe is usually provided with the enlarged head forming a funnel and the oil is picked up from the crank case and deposited in the funnel. As the oil is raised from the crank case a great deal of sediment is raised therewith and this often clogs up the oil pipe and causes the bearings to burn out and the cylinders to get dry. The 15 oil strainer and sediment trap which I have provided will fit over the funnel end of the oil pipe so as to strain the oil and catch and deposit the sediment. The oil will be raised over the top of the device and the 20 sediment will be caught on the flexible tongues 19 and as the top is inclined it will be directed over the edge of the cover. Of course the oil will pass through the opening between the tongues 19 into the funnel 25 and be conveyed through the oil pipe. The sediment carried over the edge of the cover will be caught by the outwardly turned portion 12 of the front plate and be directed into the housing and deposited on the bottom. Any oil which might be carried with the sediment will pass out through the openings or slots 11 formed in the front plate 30. When it is desired to remove the sediment, the rivet or other fastening means 35 may be removed and by swinging the extension 13 outwardly the front will be open to give access to the housing. The tongue 40 formed on the funnel, as stated above, passes through the elongated slot 16 in the back 45 and the whole device is adapted to be secured to the cylinder block by means of a screw, bolt, or other suitable fastening means which are adapted to pass through the opening 4 in the tongue 3 and through 50 the alining opening formed in the back 5.

The foregoing description and the drawings have reference to what may be considered the preferred, or approved, form of my invention. It is to be understood that I 55 may make such changes in construction and arrangement and combination of parts, materials, dimensions, etc., as may prove expedient and fall within the scope of the appended claims.

Having fully described my invention what

I claim as new and desire to secure by Letters Patent is:

1. In combination with an oil pipe, a housing surrounding the upper end of the pipe, said housing having an elongated opening formed therein, and a flexible tongue secured to the pipe and adapted to extend through the elongated opening. 65

2. In combination with an oil pipe, a housing surrounding the upper end of the pipe, said housing having an opening in the front, an outwardly extending flange formed adjacent the lower edge of the opening, and a cover provided with a plurality of openings. 70

3. In combination with an oil pipe, a housing surrounding the upper end of the pipe, said housing having an opening in front, an inclined perforated cover secured to the housing over the upper end of the pipe, said housing provided with an upwardly extending flange adjacent the lower edge of the opening, and a plurality of openings beneath the flange. 75

4. In combination with an oil pipe having a funnel at the upper end, a housing secured to the pipe, said housing having a plurality of vertically elongated openings in the front intermediate the top and bottom, a horizontal elongated opening in the front above the vertical openings, an opening in the back and an outwardly extending flange upon the lower edge of the horizontal opening in the front, a flexible tongue formed on the funnel and adapted to extend through the opening in the back of the housing, and a cover adapted to be secured to the top of the housing over the funnel, said cover having a plurality of longitudinally spaced flexible tongues adapted to be bent to engage over the upper edge of the housing. 80 90 95

5. In combination with an oil pipe having a funnel at its upper end, a housing secured to the pipe, an opening provided in the back of said housing, a flexible tongue formed on the funnel and adapted to extend through the opening in the back of the housing, and a perforated cover adapted to be secured to the top of the housing over the funnel and means provided in front of the housing for catching sediment from the top as described. 105 110

In testimony whereof I affix my signature in presence of two witnesses.

GEORGE O. EBERHARDT.
